US0D1036422S

(12) **United States Design Patent** (10) **Patent No.:** **US D1,036,422 S**
(45) **Date of Patent:** **** Jul. 23, 2024**

(54) **REMOTE CONTROL**

(71) Applicant: **Morandi Grey Inc**, Denver, CO (US)

(72) Inventor: **Yuan Chen**, Denver, CO (US)

(**) Term: **15 Years**

(21) Appl. No.: **29/861,066**

(22) Filed: **Nov. 25, 2022**

(51) **LOC (14) Cl.** **14-03**

(52) **U.S. Cl.**

USPC **D14/218**

(58) **Field of Classification Search**

(57) **CLAIM**

The ornamental design for a remote control, as shown and described.

DESCRIPTION

FIG. 1 is a perspective view of a remote control showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view of a remote control as shown. The broken lines illustrate portions of the article and form no part of the claimed design.

1 Claim, 8 Drawing Sheets
